APPARATUS FOR PROCESSING GAS

John C. Swan, Marietta, Ohio; Charles W. Swan
executor of said John C. Swan, deceased

Application June 12, 1935, Serial No. 26,223

10 Claims. (Cl. 257—28)

The invention relates to a gas processing apparatus particularly adapted for recovering gasoline from natural gas, and more especially to an apparatus by means of which it is possible to recover from the gas certain of the lighter constituents which are ordinarily not recovered as gasoline.

The invention contemplates means for rectifying crude gasoline in the same apparatus in which it is abstracted, and utilization of the same for making the process continuous.

An object of the improvement is to provide an apparatus which may receive natural gas directly from a well, or waste gases from the distillation of petroleums, especially where the petroleum is put through the process of hydrogenation, or the gases and vapors from the destructive distillation of coal, wood or other carbonaceous bodies that are plentiful and cheap, and which will economically and quickly recover a maximum amount of the gasoline from the gas so that the condensed gasoline and processed gas may be separately withdrawn from the apparatus.

An important object of the improvement is to provide means for maintaining a constant maximum level of condensed gasoline in the liquid receiving chamber and for continuously withdrawing condensed gasoline from said chamber at such a rate that this constant maximum level will be maintained throughout the process.

The above and other objects may be attained by providing a casing surrounded by a spaced jacket, both of which are constructed of structural metal members of sufficient strength to withstand the pressures and temperatures to which the gases therein are subjected, the jacket being preferably reinforced by transversely or laterally disposed structural members alternately arranged on opposite sides of the jacket and clamped thereon as by tie bolts or bars; the casing being divided by means of spaced transverse partition walls into an upper condensing chamber, a central refrigerant chamber and a lower gasoline receiving chamber, the side walls of the condensing chamber being perforate to provide communication with the gas receiving space between the casing and jacket, and a multiplicity of condensing tubes being located through the refrigerant chamber and communicating at opposite ends with the condensing chamber and the gasoline receiving chamber, a float operated discharge valve being located in the gasoline receiving chamber.

It should be understood that instead of a single unit as shown in the drawing, the machine may

comprise a series of such units connected together and so arranged that the gas may be passed from one unit to the next, each unit of the apparatus being arranged to abstract a different constituent or constituents from the gas. 5

An embodiment of the invention thus briefly described is illustrated in the accompanying drawing, in which

Figure 1 is a vertical sectional elevation of an apparatus constructed in accordance with the invention; 10

Fig. 2, a transverse section taken as on the line 2—2, Fig. 1; and

Fig. 3, an enlarged fragmentary sectional elevation showing the manner of connecting the 15 condensing tubes to one of the partition plates in the casing.

Similar numerals refer to similar parts throughout the drawing.

The gas processing apparatus to which the invention pertains may be mounted upon a base 20 formed of concrete or the like, preferably having a recess 11 formed therein for a purpose to be later described. The outer jacket comprises the side walls 12 and top and bottom walls 13 and 25 14 respectively, the side walls being formed of structural members, preferably vertically disposed channel members 15, the flanges 16 of which may be inturned and welded together and provided with openings 17 to permit free passage 30 of gas therethrough.

The casing, indicated generally at 18, is spaced within the jacket and formed of structural members such as the vertically disposed I-members 19, the flanges 20 of which may be riveted together and provided with apertures 21 which, together with the apertures 17 in the flanges 16, permit free circulation of the gas between the casing and jacket. Angle members 22 may be provided at the corners of the casing and welded 40 to the flanges 20 of adjacent I-members, the apertures 21 extending through said angle members as well as the flanges 20. 35

As best shown in Fig. 2, it will be seen that the flanges 16 and 20 form spacers between the casing and the jacket, thus providing the desired space between these two members and at the same time reinforcing and bracing both the casing and the jacket and together with the transversely disposed structural reinforcing members 50 to be later described, providing a rigid solid construction of sufficient strength to withstand the pressures and temperatures to which the apparatus is subjected. 45

The reinforcing structure includes alternately 55

staggered pairs of structural members such as the T-bars 23 transversely disposed around the jacket and clamped thereon as by the tie bolts or bars 24.

5 It should be understood that the top plate 13 and the bottom plate 14 are welded to the adjacent end portions of the jacket as well as the casing in order to provide an entirely gas-tight structure.

10 Transversely disposed partition plates 25 and 26 are located within the casing, spaced from the upper and lower ends thereof respectively, the edges of said partition plates being tightly welded to the inner walls of the casing in order to provide gas-tight joints. These partition plates divide the casing into the upper or condensing chamber 27, the central or refrigerant chamber 28 and the lower or gasoline receiving chamber 29.

15 Between the upper partition plate 25 and the top plate 13 the side walls of the casing are perforated as at 30, forming a communication between the condensing chamber 27 and the gas receiving chamber between the casing and jacket.

20 A multiplicity of longitudinally disposed refrigerant tubes 31 is located through the refrigerant chamber, the opposite ends of the tubes being located through suitable apertures 32 in the upper and lower partition plates 25 and 26 25 and welded thereto as shown at 33, thus producing a gas-tight joint between the tubes and the partition plates, as well as reinforcing the latter.

25 A gas inlet pipe 34 extends through the outer jacket 12 communicating with the gas receiving space between the jacket and the casing 18, this inlet pipe being connected to a gas well or any suitable source of supply of natural gas. A gas discharge pipe 35 communicates with the upper portion of the gasoline receiving chamber 29 and it may discharge into the atmosphere or be connected to any suitable container for receiving the same.

30 A float controlled discharge valve is located in the lower portion of the gasoline receiving chamber 29 and may include a casting or the like 36 having a gasoline discharge passage 37 formed therein, provided at its upper end with a valve seat 38 for the valve 39, having the ears 40 pivotally connected as at 41 to the float arm 42 which is pivoted as at 43 upon a lug 44 which may be formed upon the casting 36, a float ball 45 being located at the free end of the arm. A yoke 46, upon the casting 36, may be provided to guide the float arm 42.

35 The casting 36 may be provided with a depending threaded nipple 47 located through an aperture 48 in the bottom wall 14 upon which is screwed the casting or the like 49 having a gasoline discharge passage 50 registering with the passage 37 into which may be connected the gasoline discharge pipe 51 which may lead to any suitable storage place for the gasoline. The valve 39 may be provided with a depending rod 52 located through the discharge passage 37 and into the passage 50.

40 For the purpose of manually operating the valve to open the same in the event it should by any means become stuck, a hand operated lever 53 may be pivoted as at 54 upon a lug 49a formed on the casting 49, a rod 55 being pivoted as at 56 upon said lever and located through a stuffing box 57 in the casting 49, said rod being arranged to contact the rod 37 in order to manually raise

the valve 39. A yoke 58 may be formed upon the casting 49 to guide the hand lever 53.

45 A refrigerant liquid inlet pipe 59 may be located through the jacket and casing into the lower portion of the refrigerant chamber 28 and a refrigerant vapor outlet pipe 60 may communicate with the upper portion of the refrigerant chamber and extend outward through the casing and jacket and communicate with any suitable receiving apparatus such as a compressor or the like.

50 In order to speed up the operation when the process is first started, instead of first introducing the gas to be processed, the machine may be first charged with light gasoline obtained from any 15 source other than the source from which the gas to be processed is to be obtained. Only a relatively small amount of this light gasoline is necessary, all that is required being that a sufficient quantity of the same be charged into the apparatus to cause condensation in the carrier gas to be later processed.

55 Low pressure is established on the surface of the inserted gasoline, causing cooling evaporation to cool the elements of the machine to working temperature before admitting the gas to be processed. In this manner I obtain a refrigeration of the operating machine which is to receive further wet gas for processing.

60 The natural gas to be processed is admitted to the gas receiving chamber between the casing and jacket through the gas inlet pipe 34, under a pressure of about 1600 pounds, and passes through the apertures 17 in the flanges of the structural members entirely surrounding the casing and rises to the top of the apparatus, passing through the apertures 30 in the side walls of the casing into the condensing chamber 27 and then downward through the refrigerant tubes 31.

65 At the same time, the refrigerant liquid, which may be propane, having a boiling temperature of -45° C., is admitted to the refrigerant chamber through the liquid refrigerant inlet pipe 59, entirely surrounding the refrigerant tubes 31 and liquefying a considerable part of the gas in said 45 tubes, the gasoline thus produced passing downward from the tubes into the gasoline receiving chamber 29 where it collects in the lower part of said chamber as indicated at G.

70 As the liquid gasoline level in the chamber 29 rises, the float operated valve 39 will be opened, discharging the gasoline through the pipe 51 to any suitable storage place, while the processed gas may be withdrawn from the chamber 29 through the gas outlet pipe 35 where it may either be discharged into the atmosphere or conveyed to any suitable point. As the refrigerant vapors rise in the refrigerant chamber, they may be withdrawn through the outlet pipe 60 and conveyed to a condenser or other suitable apparatus.

75 I claim:

1. Apparatus for processing gas including a jacket, a casing spaced within said jacket and forming a gas receiving chamber therebetween, means for admitting gas under pressure to said receiving chamber, said casing having a condensing chamber at one end communicating with said receiving chamber, an intermediate refrigerant chamber, and a condensed liquid receiving chamber beyond the refrigerant chamber, refrigerant tubes located in the refrigerant chamber and communicating at opposite ends with the condensing chamber and the liquid receiving chamber, means for admitting refrigerant liquid to the refrigerant chamber, means for withdraw-

ing refrigerant vapor from the refrigerant chamber, means for maintaining a constant maximum level of condensed gasoline in the liquid receiving chamber and for continuously withdrawing gasoline from said chamber, and means for withdrawing processed gas from the liquid receiving chamber.

2. Apparatus for processing gas including a jacket, a casing spaced within said jacket and forming a gas receiving chamber therebetween, means for admitting gas under pressure to said receiving chamber, said casing having a condensing chamber at one end communicating with said receiving chamber, an intermediate refrigerant chamber, and a condensed liquid receiving chamber beyond the refrigerant chamber, refrigerant tubes located in the refrigerant chamber and communicating at opposite ends with the condensing chamber and the liquid receiving chamber, means for admitting refrigerant liquid to the refrigerant chamber, means for withdrawing refrigerant vapor from the refrigerant chamber, means for maintaining a constant maximum level of condensed liquid in the liquid receiving chamber and for continuously withdrawing condensed liquid from the liquid receiving chamber, and means for withdrawing processed gas from the liquid receiving chamber, alternately staggered pairs of transversely disposed structural bars located around said jacket, and tie bolts clamping said structural bars around the jacket.

3. Apparatus for processing gas including a jacket formed of longitudinally disposed structural members provided with flanges, a casing within the jacket formed of longitudinally disposed structural members having flanges, said flanges spacing the casing and jacket and forming a gas receiving chamber therebetween, means for admitting gas under pressure to said receiving chamber, said casing having a condensing chamber at one end communicating with said receiving chamber, an intermediate refrigerant chamber, and a condensed liquid receiving chamber beyond the refrigerant chamber, refrigerant tubes located in the refrigerant chamber and communicating at opposite ends with the condensing chamber and the liquid receiving chamber, means for admitting refrigerant liquid to the refrigerant chamber, means for withdrawing the refrigerant vapor from the refrigerant chamber, means for maintaining a constant maximum level of condensed liquid in the liquid receiving chamber and for continuously withdrawing condensed liquid from the liquid receiving chamber, and means for withdrawing processed gas from the liquid receiving chamber.

4. Apparatus for processing gas including a jacket formed of longitudinally disposed structural members provided with flanges, a casing within the jacket formed of longitudinally disposed structural members having flanges, said flanges spacing the casing and jacket and forming a gas receiving chamber therebetween, said flanges having openings therethrough, means for admitting gas under pressure to said receiving chamber, said casing having a condensing chamber at one end communicating with said receiving chamber, an intermediate refrigerant chamber, and a condensed liquid receiving chamber beyond the refrigerant chamber, refrigerant tubes located in the refrigerant chamber and communicating at opposite ends with the condensing chamber and the liquid receiving chamber, means for admitting refrigerant liquid to the refrigerant chamber, means for withdrawing

ing refrigerant vapor from the refrigerant chamber, means for maintaining a constant maximum level of condensed liquid in the liquid receiving chamber and for continuously withdrawing condensed liquid from the liquid receiving chamber, and means for withdrawing processed gas from the liquid receiving chamber.

5. Apparatus for processing gas including a jacket formed of longitudinally disposed structural members provided with flanges, a casing within the jacket formed of longitudinally disposed structural members having flanges, said flanges spacing the casing and jacket and forming a gas receiving chamber therebetween, means for admitting gas under pressure to said receiving chamber, said casing having a condensing chamber at one end communicating with said receiving chamber, an intermediate refrigerant chamber, and a condensed liquid receiving chamber beyond the refrigerant chamber, refrigerant tubes located in the refrigerant chamber and communicating at opposite ends with the condensing chamber and the liquid receiving chamber, means for admitting refrigerant liquid to the refrigerant chamber, means for withdrawing refrigerant vapor from the refrigerant chamber, means for maintaining a constant maximum level of condensed liquid in the liquid receiving chamber and for continuously withdrawing condensed liquid from the liquid receiving chamber, and means for withdrawing processed gas from the liquid receiving chamber, alternately staggered pairs of transversely disposed structural bars located around said jacket, and tie bolts clamping said structural bars around the jacket.

6. Apparatus for processing gas including a jacket formed of longitudinally disposed structural members provided with flanges, a casing within the jacket formed of longitudinally disposed structural members having flanges, said flanges spacing the casing and jacket and forming a gas receiving chamber therebetween, said flanges having openings therethrough, means for admitting gas under pressure to said receiving chamber, said casing having a condensing chamber at one end communicating with said receiving chamber, an intermediate refrigerant chamber, and a condensed liquid receiving chamber beyond the refrigerant chamber, refrigerant tubes located in the refrigerant chamber and communicating at opposite ends with the condensing chamber and the liquid receiving chamber, means for admitting refrigerant liquid to the refrigerant chamber, means for withdrawing refrigerant vapor from the refrigerant chamber, means for maintaining a constant maximum level of condensed liquid in the liquid receiving chamber and for continuously withdrawing condensed liquid from the liquid receiving chamber, and means for withdrawing processed gas from the liquid receiving chamber, alternately staggered pairs of transversely disposed structural bars located around said jacket, and tie bolts clamping said structural bars around the jacket.

7. Apparatus for processing gas including a jacket formed of longitudinally disposed structural channel beams, a casing within the jacket formed of longitudinally disposed structural I-beams, the flanges of said channel beams and I-beams spacing the casing and jacket and forming a gas receiving chamber therebetween, means for admitting gas under pressure to said receiving chamber, said casing having a condensing chamber at one end communicating with said

- 5 receiving chamber, an intermediate refrigerant chamber, and a condensed liquid receiving chamber beyond the refrigerant chamber, refrigerant tubes located in the refrigerant chamber and communicating at opposite ends with the condensing chamber and the liquid receiving chamber, means for admitting refrigerant liquid to the refrigerant chamber, means for withdrawing refrigerant vapor from the refrigerant chamber, 10 means for maintaining a constant maximum level of condensed liquid in the liquid receiving chamber and for continuously withdrawing condensed liquid from the liquid receiving chamber, and means for withdrawing processed gas from 15 the liquid receiving chamber.
8. Apparatus for processing gas including a jacket formed of longitudinally disposed structural channel beams, a casing within the jacket formed of longitudinally disposed structural 20 I-beams, the flanges of said channel beams and I-beams spacing the casing and jacket and forming a gas receiving chamber therebetween, said flanges having openings therethrough, means for admitting gas under pressure to said receiving 25 chamber, said casing having a condensing chamber at one end communicating with said receiving chamber, an intermediate refrigerant chamber, and a condensed liquid receiving chamber beyond the refrigerant chamber, refrigerant 30 tubes located in the refrigerant chamber and communicating at opposite ends with the condensing chamber and the liquid receiving chamber, means for admitting refrigerant liquid to the refrigerant chamber, means for withdrawing refrigerant vapor from the refrigerant chamber, 35 means for maintaining a constant maximum level of condensed liquid in the liquid receiving chamber and for continuously withdrawing condensed liquid from the liquid receiving chamber, and 40 means for withdrawing processed gas from the liquid receiving chamber.
9. Apparatus for processing gas including a jacket formed of longitudinally disposed structural channel beams, a casing within the jacket formed of longitudinally disposed structural 45 I-beams, the flanges of said channel beams and I-beams spacing the casing and jacket and forming a gas receiving chamber therebetween, means for admitting gas under pressure to said receiving chamber, said casing having a condensing 50 chamber at one end communicating with said receiving chamber, an intermediate refrigerant chamber, and a condensed liquid receiving chamber beyond the refrigerant chamber, refrigerant tubes located in the refrigerant chamber and communicating at opposite ends with the condensing chamber and the liquid receiving chamber, means for admitting refrigerant liquid to the refrigerant chamber, means for withdrawing refrigerant vapor from the refrigerant chamber, 10 means for maintaining a constant maximum level of condensed liquid in the liquid receiving chamber and for continuously withdrawing condensed liquid from the liquid receiving chamber, and means for withdrawing processed gas from the 15 liquid receiving chamber, alternately staggered pairs of transversely disposed structural bars located around said jacket, and tie bolts clamping said structural bars around the jacket.
10. Apparatus for processing gas including a 20 jacket formed of longitudinally disposed structural channel beams, a casing within the jacket formed of longitudinally disposed structural I-beams, the flanges of said channel beams and I-beams spacing the casing and jacket and forming a gas receiving chamber therebetween, said flanges having openings therethrough, means for admitting gas under pressure to said receiving 25 chamber, said casing having a condensing chamber at one end communicating with said receiving chamber, an intermediate refrigerant chamber, and a condensed liquid receiving chamber beyond the refrigerant chamber, refrigerant 30 tubes located in the refrigerant chamber and communicating at opposite ends with the condensing chamber and the liquid receiving chamber, means for admitting refrigerant liquid to the refrigerant chamber, means for withdrawing refrigerant vapor from the refrigerant chamber, 35 means for maintaining a constant maximum level of condensed liquid in the liquid receiving chamber and for continuously withdrawing condensed liquid from the liquid receiving chamber, and means for withdrawing processed gas from the 40 liquid receiving chamber, alternately staggered pairs of transversely disposed structural bars located around said jacket, and tie bolts clamping said structural bars around the jacket.
